UNITED STATES PATENT OFFICE.

LEONARD KNETZGER, OF DUQUOIN, ILLINOIS.

CRIMPING-MACHINE FOR BOOTS AND SHOES.

SPECIFICATION forming part of Letters Patent No. 350,065, dated September 28, 1886.

Application filed June 25, 1886. Serial No. 206,249. (No model.)

To all whom it may concern:

Be it known that I, LEWIS KNETZGER, of Duquoin, Perry county, in the State of Illinois, have invented new and useful Improvements in Crimping-Machines; and I do hereby declare that the following is a full and accurate description of the same.

Heretofore Letters Patent Nos. 165,977 and 177,483 were granted to me for machines for stretching and crimping leather, and my present invention, described herein, relates to improvements in said invention; and it consists, first, in the device for laterally stretching the edge of the leather blank; second, in the device for completely stretching the edges and corners of the blank; and, third, in the devices whereby all the several operations are conducted and completed on a single machine.

Figure 1 is a perspective of my machine. Fig. 2 is a vertical section of the same. Fig. 3 is a perspective view of the boot-upper as it comes from the crimpler. Fig. 4 is a perspective view of the same as it comes from the stretcher and finisher. Fig. 5 is an elevation showing the finisher-saddle for shoe-uppers. Fig. 6 is a perspective view of the crimpler-blade with stretching-ribs.

The frame of my machine consists, essentially, of two standards, A, longitudinally grooved on their inner sides to constitute guides for the sliding crimpler B. The standards A are connected at top by the head-frame C, and at bottom by the cross-bar D, and are provided with feet E. A table, F, is attached to the standards to support the blank while the stretching-blade is acting. Said table is made in two parts, slightly separated to permit the stretcher to pass between them, and relatively adjustable to permit them to be adapted to different thicknesses of leather. Changes in this adjustment are effected by means of screw-nuts *a* on the tie-rods G. A clamp, H, is placed above the table F to clamp and hold the leather during the action of the stretcher with sufficient pressure to insure the proper stretching of the leather. The clamp H is depressed by springs I, one at each end, the tension of which may be varied as desired, by means of tension-screws or other means usual in such cases. The lower edge, *t*, of the crimping-stretcher B is formed approximately in the shape of the instep, ankle, and leg of

the boot, and is provided on each side with two laterally-projecting ribs, *k* *k*, and the table F has notches *n*, corresponding with said ribs *k*, into and through which said ribs pass when the stretcher descends. The purpose of these ribs is to stretch the edge of the blank so that the crimp may be obtained with a crimping-edge more nearly straight than can otherwise be used. This is shown in Fig. 3, and was fully explained in my Patent No. 165,977. In my said patent only a single rib on each side of the former is employed; but I have found for many grades of leather it is inexpedient to force the entire required stretch at one point. I therefore employ herein two or more ribs *k*, and thus distribute the stretch at a corresponding number of points along the edge of the blank, as shown at *p*, Fig. 3. The clamp is automatically raised by lugs *q*, which project laterally from the sides of the crimpler B beneath said clamp. They are located so that on the upward stroke of said crimpler they engage said clamp after said crimpler has passed out of the matrix, and vice versa on the downstroke the clamp engages the leather before the crimpler arrives.

The stretcher B is provided along its vertical edge with a rack, *l*, in engagement with a pinion, *m*, on the shaft *w*, and operated by the lever O. When said levers are pulled over a horizontal position, the crimpler is forced to descend, and when said lever returns to its initial position said crimpler ascends again to its initial position. The blank is laid upon the table in proper position with its median line under the edge of the stretcher. The lever O is then pulled over and the stretcher and clamp descend upon the table. The clamp holds the leather with considerable pressure, so that as the leather is forced down through the opening in the table the resistance of the clamp causes it to be stretched to conform approximately to the form of the stretcher. After being crimped and stretched, as described above, the blank still needs a finishing stretch before it will acquire its desired final shape and finish. I therefore place at the top of the frame A the frame or matrix bars C, which are adjustable as to each other to increase or diminish the space between, according to the thickness of the leather and the former, which is constituted by the upper edge, *r*, of the

stretching-plate B, and is brought into action when the plate B is moved upward by the lever O. The form of the edge *r* is that which is proper for the finished crimped upper, and the lower edge of the matrix is correspondingly shaped, but with the point *u* prominent, so it will encounter the leather first near the instep, and will progressively stretch it in both directions therefrom, the effect being a continuous stretch in the line of movement, and also lateral thereto in both directions. The leather is thereby stretched completely and uniformly throughout and to the edges. It frequently happens, however, that it is desired to stretch blanks for shoes, or those which are less than a whole upper, and it is sometimes desirable, also, to vary the shape, and I have therefore provided a saddle-piece, S, adapted to fit over and be secured to the stretcher *r*, having its working-edge in the required shape. Saddle-pieces S may be provided in such variety as may be needed to suit the different sizes or shapes of uppers.

Having described my invention, I claim--

1. In a crimping-machine, the divided table F, with adjustable tension-pressure springs on rods G, combined with the stretching-plate B, fitted to slide in the frame A, the clamp H, and the operative racks *l*, pinion *m*, and lever O, substantially as set forth.
2. The stretching-plate B, provided with

two or more laterally-projecting ribs *k*, combined with the divided table F, provided with lateral-extending notches *n*, corresponding with said ribs, whereby the edge of the blank is stretched at several points, as set forth.

3. In a crimping and stretching machine, the plate B, fitted to slide in the frame A, and provided on its free ends with the crimping and stretching edges *t* and *r*, respectively, combined with the crimping-table F, clamp H, matrix C, and means for actuating said plate B, as set forth.

4. In a crimping and stretching machine, a divided table, F, a clamp, H, held down upon said table by springs, combined with a stretching plate or blade provided with lugs *g*, to engage and automatically raise said clamp when said stretching-plate is retracted, substantially as set forth.

5. In a crimping and stretching machine, a stretching plate or blade, and a matrix, combined with a removable saddle-piece, S, adapted to fit on and be secured to said blade, whereby the form of the working edge of the stretcher may be varied, as set forth.

LEONARD KNETZGER.
